UNITED STATES PATENT OFFICE.

ALBERT REDDLE THOMSON, OF PLANTSVILLE, CONNECTICUT.

PICKAX.

1,369,499.

Specification of Letters Patent. Patented Feb. 22, 1921.

Application filed May 13, 1919, Serial No. 296,877. Renewed November 2, 1920. Serial No. 421,409.

To all whom it may concern:

Be it known that I, ALBERT REDDLE THOMSON, a citizen of the United States, residing at Plantsville, in the county of Hartford and State of Connecticut, have invented certain new and useful Improvements in Pick-axes, of which the following is a specification.

My invention relates to improvements in pickaxes, and has particular reference to the blade or bit portion of pickaxes having certain features that are common to the form of pickax shown and described in my Patent No. 1,262,870, April 16, 1918, and other features that are novel in the form shown herewith, and the object of my improvement is to produce a pickax in which the blade or bit portion is constructed so as to have the necessary and proper strength for service and utility and which is made by a process that provides for economical use of material, in that a bar of stock of smaller size may be used in the production thereof.

In the accompanying drawing:

Figure 1 is a side elevation of a pickax.

Fig. 2 is a side elevation of one of the bit members shown in Fig. 1.

Fig. 3 is an end elevation of the structure shown in Fig. 1.

Fig. 4 is a sectional view, on an enlarged scale, on the line 4—4 of Fig. 1.

Fig. 5 is a sectional view on the line 5—5 of Fig. 3.

Fig. 6 is a side elevation of a bar of stock that is used for making the bit member shown in Fig. 2.

Fig. 7 is a side elevation of the same after having been operated upon by the forming dies.

Fig. 8 is a side elevation of the same after being trimmed.

Fig. 9 is a sectional view on the line 9—9 of Fig. 8.

Fig. 10 is a sectional view on the line 10—10 of Fig. 8.

My improved pickax comprises a head 10 having a transverse opening 11 for a handle 12 in the middle or body portion 13 and having branches 14 extending upwardly and downwardly from the said body 13, one on each side, for removably receiving the bit members 15, the said branches 14 being each provided with a slot 16 that extends through from front to rear for providing access to the inner end of the bit member 15 for the

purpose of driving the bit member 15 from the branch 14 when it is desired to change the bit member.

The manner of securing the bit member 15 in the branch or arm 14 corresponds to that shown and described in the patent mentioned, and comprises, accordingly, a socket 17 of peculiar form in the said branch 14 that is a fit for the stem 18 on the inner end of the bit member 15. Thus the socket 17 has parallel and straight side walls 19 that are cross-connected at the front and at the back in each case by two end wall sections 20 that extend inwardly from the two side walls 19 at an inclination other than a right angle so as to meet at the middle or apex 21 at an appreciable angle, so as to provide a V-shape. The end wall sections 20 serve as the contact wall portions of the socket 17 for contacting with the opposed end wall 70 portions or sections 22 of the stem 18, a clearance space 23 being provided between the parallel side walls 19 of the socket 17 and the opposed side walls of the stem 18 on each side. The V-shaped wall formed by 80 the two wall sections 20 may conveniently be designated as the roof of the socket 17 at one end of the section and as the bottom at the other end thereof; the said roof and bottom serving as the holding portions of 85 the socket 17.

Also, the V-shaped walls of the stem 18 may be conveniently designated as the top wall at one end of the section and the bottom wall at the other end thereof, each being formed by a pair of wall sections 22.

Thus the V-shaped wall structures described serve as the active holding walls and the side walls 19 of the socket 17 and the opposed side walls of the stem 18 are inactive so far as concerns any holding effect.

The said opposed side walls of the stem 18 are designated generally by the character 24, and it will be noted that these walls have an inwardly curved or reentrant form for 100 the major part of the length of the stem 18, and for the major part of the width of the stem 18, as shown. A border portion 25 adjacent the outer corners 26 of the top wall sections 22 and the bottom wall sections 22 105 may be flat and parallel with the axis of the cross section. Thus the cross section of the stem 18 comprises generally the form of an I-beam, having enlarged portions 28 along the top and bottom edges that are 110

connected by the intermediate web portion 29.

At the extreme end portion 30 of the stem 18 the sides 31 may be filled out so as to be 5 straight across the corners 26 so that the said end portion 30 will be adapted to serve as a driving head for driving the bit member 15 from the socket 17 by means of a wedge, and for which purpose an extra bit member 15 would generally be used. The 10 stem 18 is tapered longitudinally from the inner end portion 32 outwardly toward the end 30.

The peculiar form provided for the stem 15 18 provides a stem structure that has all of the useful and necessary qualities such as pertain to holding in place and strength, particularly as compared with a structure having flat and parallel side walls, and these 20 results are obtained by a construction that permits of a reduction in the size of stock that can be used for making the stem 18.

In a stem structure having parallel side walls the bar stock used must have a cross 25 section as large as the cross section of the largest part of the stem, which would correspond to the position of the inner end portion 32, so that the size of the stem would stand as a determining factor in selecting 30 the size of the stock. That is to say, the cross section of the stem would determine what the minimum size of stock must be. Actually, however, in the case of bit members having parallel sides, such as are now 35 in common use, the size of the stock used is determined by the cross section at the widest part 33 of the body portion 34 of the bit member 15, which is at some position intermediate the stem 18 and the bit 35 at the 40 tip, and which has an appreciably greater area of cross section than any part of the stem.

The contour of the bit member 15 shown 45 corresponds generally to that of bit members referred to as being in common use, and comprises a bottom edge 36 that is substantially straight and a top edge 37 of rounded, convex form, with the widest portion 33 of the structure appreciably remote from the 50 stem 18.

I find that by continuing the I-beam form of cross section along outwardly from the stem 18 longitudinally along the body portion 34 up to the inner end 38 of the bit portion 35 that I can and do obtain a distribution 55 of the material of the bar stock in the cross sectional structure such that the size of the

bar stock used is determined by the cross section at 38 which corresponds to the junction of the body portion 34 and the bit portion 35.

The cross section at the said junction 38 is preferably substantially rectangular and solid, and the area thereof is appreciably less than the area of the cross section of the 60 stem 18 would be if not reduced as described, but sufficiently large to equal the area of the cross section of the reduced stem structure, and also provide material for the body portion 34, of the I-beam form as described. 70

I find that in the forming operation by means of dies there is a longitudinal flow of metal so as to form a bit 35 of full length, with tapered form, from a bar 40 of stock 75 that is appreciably shorter than the overall length of the bit member 15, and with one operation.

It is common to reduce the bar stock to form the tapered bit before shaping the 80 body and stem, but this preliminary operation is omitted by my improved process.

Thus the dies operate on the bar 40 and produce substantially the finished bit member 15, except for the fin or flash 41, which 85 is trimmed off.

I find that by using a bar 40 of $\frac{5}{8}$ inches in diameter I can produce a bit member having a cross section of rectangular form having the dimensions $\frac{1}{2}$ inch by $\frac{5}{8}$ inches at 90 the junction 38, and having the overall dimensions for the body at the widest part about $\frac{1}{2}$ inch by $1\frac{1}{4}$ inches and for the stem $\frac{1}{2}$ inch by one inch.

Thus by my invention there is a saving of 95 material, and the tool produced is adapted to meet the usual requirements for service and efficiency.

I claim as my invention:—

A bit member for a pickax comprising 100 a stem at one end, a tapered bit at the other end, and a body intermediate the said ends, having a generally uniform overall thickness from the outer end of the said stem to the junction of the said body and bit and a 105 width for the said stem and body generally appreciably in excess of the width at the said junction, and the said stem and body having reduced portions along the longitudinal axis so that the cross section of the 110 material will not exceed the cross section of the material at the said junction.

ALBERT REDDLE THOMSON.
